INVENTOR
C. L. Whipple

UNITED STATES PATENT OFFICE.

CHARLES L. WHIPPLE, OF LOS ANGELES, CALIFORNIA.

BOOK-HOLDER AND ADVERTISING DEVICE.

SPECIFICATION forming part of Letters Patent No. 535,970, dated March 19, 1895.

Application filed November 22, 1894. Serial No. 529,667. (No model.)

To all whom it may concern:

Be it known that I, CHARLES L. WHIPPLE, of Los Angeles, in the county of Los Angeles and State of California, have invented certain new and useful Improvements in a Combined Book - Holding and Advertising Device, of which the following is a full, clear, and exact description, reference being had to the accompanying drawings, which form a part of this specification.

My invention relates to certain new and useful improvements in combined book holding and advertising devices, intended more especially for directories and other books exposed in hotels and other public places, where it is desired to prevent the book from being removed or stolen, and to display advertising matter, but which also serves for offices and other private use; and my invention consists in certain features of novelty hereinafter described and claimed.

Figure I represents a side elevation of a stand having a revolving top and my improved book holding and advertising frame supported thereon. Fig. II is a top view. Fig. III is a vertical section taken on line III, III, Fig. II, but showing the book closed in full lines. Fig. IV represents the inside of one of the hinged leaves for holding the book. Fig. V is a section taken on line V, V, Fig. IV.

Referring to the drawings, 1 represents a stand having a revolving box top 2, with a central chamber or space 3. The bottom, section 4, of the box top is pivoted at 5 to the supporting post 6. The upper section 7 of the top has a central aperture 8.

9 represents lugs secured at 10 to the under side of the top section 7.

11 represents leaves having pockets 12 of proper dimensions to take in the cover of a book, said cover being firmly held in the pockets by means of screws 13 which pass through the material forming the pockets and through the cover.

14 represents lugs on the back of the leaves 11, said lugs being pivoted at 15 to the lugs 9.

By the above described means the book may be opened and remain open by its own weight, as shown in dotted lines, Fig. III, or closed up and held closed by its own weight, as shown in full lines Fig. III and at the same time remain firmly locked to the stand. As the book is closed it recedes partly through the aperture 8 into the chamber 3.

16 represents a skeleton frame surrounding the space the book occupies and covering the remaining portion of the top of the stand, said frame having a number of spaces 17 for holding advertising matter or other matter of information; the matter in said spaces being covered with glass 18 to protect the same.

I claim as my invention—

1. A combined book-holding and advertising device comprising a support, a top formed with an upper section having a book-aperture, the pendent lugs secured to the under side of the upper section, the leaves having pockets for the reception of the book-covers, and lugs located on the backs of the leaves and pivoted to the pendent lugs, and the skeleton advertising frame secured to the upper section and having card spaces surrounding the book aperture; substantially as described.

2. A combined book-holding and advertising device comprising a stand having a revolving box-top formed with a central chamber, a lower section, and an upper section having a book-aperture, the supporting post to which the lower section is pivoted, the pendent-lugs secured to the under side of the upper section, the leaves having pockets for the reception of the book-covers and lugs located on the backs of the leaves and pivoted to the pendent lugs, and the skeleton advertising frame secured to the upper section and having card spaces surrounding the book-aperture; substantially as described.

CHARLES L. WHIPPLE.
